UNITED STATES PATENT OFFICE.

CARYL D. HASKINS, OF SCHENECTADY, NEW YORK, ASSIGNOR TO GENERAL ELECTRIC COMPANY, A CORPORATION OF NEW YORK.

PERIODIC CIRCUIT-CLOSER.

SPECIFICATION forming part of Letters Patent No. 727,625, dated May 12, 1903.

Application filed August 9, 1901. Serial No. 71,494. (No model.)

To all whom it may concern:

Be it known that I, CARYL D. HASKINS, a citizen of the United States, residing at Schenectady, in the county of Schenectady, State of New York, have invented certain new and useful Improvements in Periodic Circuit-Controllers, (Case No. 2,163,) of which the following is a specification.

This invention relates to circuit-controllers designed to be operated at determinate time periods to cut into or out of operation at such periods electric circuits, including translating devices.

The object of the invention is to provide a device of this character which may operate at long intervals, which will be of a simple and durable construction, and may be relied upon to perform its functions continuously without the attention of an operator. Devices having the same general purpose in view have been heretofore provided controlled in operation by clockwork, which is released by a time-train at determinate intervals. Such devices have the disadvantage of possible failure through lack of attention in oiling or winding the clockwork and through inherent disability due to the delicacy of the apparatus.

In carrying out my invention I provide a rotative reservoir in which is contained a mobile material and constructed so that the material can flow from one chamber to another and means by which the device may be rotated after a determinate amount of material has been so transferred. When shifted to either of its operating positions, the transfer from one chamber to another begins, and after a definite time interval the device operates an electric circuit, which shifts it in position and effects retransfer to the original chamber. In shifting from one position to another it actuates the circuit it is designed to control.

The invention embodies various features of novelty, which will be more fully herein-after described, and will be definitely indicated in the claims appended to this specification.

In the accompanying drawings illustrating the invention, Figure 1 is a diagrammatic illustration showing a periodic circuit-con-

troller embodying my invention in operative relation to a controlled circuit. Fig. 2 is a sectional view showing the construction of the periodic controller.

55

Referring first to Fig. 2, 1 represents a reservoir, which may be conveniently of hour-glass form with screw-joints, as indicated, by which it may be assembled and taken apart. It is provided with two connected chambers 1^a 1^b and is mounted on a shaft 2, supported in bearings, so as to be capable of free rotation. The shaft carries a pinion 3, by which the device may be revolved. I employ within the hollow structure a mobile material capable of transfer from one chamber to the other. I preferably employ for this purpose a conducting liquid, such as mercury, though it is not absolutely essential that conducting material be employed, 70 since a non-conducting material might be used in connection with a float to control the circuit-contacts. Mercury or a similar conductor, however, is preferred on account of the simplicity of construction. The walls 75 of the vessel in such case should be formed of iron, glass, or some material which does not amalgamate. The two chambers are connected by two tubes 4 5, having fine bores, each of which connects the outer end of a chamber 80 with the inner end of the other chamber. Each chamber is provided with a pair of insulating-contacts 6 6^a 7 7^a, electrically connected with insulated contact-rings 6^b 6^c and 7^b 7^c, on which bear brushes 8 8^a 9 9^a, leading 85 to operating devices for shifting the controller, as will be hereinafter more fully described. The contacts 6^a 7^a are adjustable, so as to change the time interval before contact is made with the mercury.

90

In gear with the pinion 3 is an iron rack 10, coöperating with control-magnets 11 11^a, and in order to give a long throw the rack is provided with tapered extremities, as indicated in Fig. 1, and coöperates with tapering recesses in the core of the electromagnets.

95

The circuit through the magnets is controlled by the insulated contacts through the brushes above described. 12 represents a circuit containing translating devices or other apparatus to be periodically operated. I have shown in the diagram an arc-lamp circuit

100

containing a group of lamps, as shown at 13, which it may be desired to operate at determinate intervals. For example, it is not unusual to cut in and out at determinate hours 5 of the night a group of lamps in a store or other place where the current is furnished on contract. This may be easily effected by the employment of my periodic circuit-controller, which at determinate intervals may operate 10 an electromagnet 14, governing a switch 15, controlling the group of lamps. The operating-current for the control-circuit may be furnished from any source. For example, it may be derived from the arc-lamp circuit, as by 15 means of a shunt around a resistance 16.

Assuming the devices in the position indicated in Fig. 2, when the arc-light circuit 12 is energized a circuit through magnet 11 will be closed over wire 17, brush 8^a, contact-ring 20 6^b, contact 6, mercury bridge, contact 6^a, ring-contact 6^c, brush 8, wire 18, coils of magnet 11, wire 19, thus permitting resistance 16 to 25 shunt an operating-current through magnet 11, which draws the rack 10 to the left, and thereby inverts the reservoir and simultaneously shifts switch 20, energizing magnet 14 and closing switch 15. The lamps in circuit 30 13 are thus started. Mercury then slowly escapes from chamber 1^b to 1^a. The rate of flow may be, if desired, drop by drop and the 35 contact 7^a may be set for the period the lamps 13 are to burn, at the end of which period contacts 7 7^a will be bridged and magnet 11^a energized over circuit 17, coil of 11^a, wire 21, 40 brush 9^a, contact-ring 7^b, contact 7, mercury bridge, contact 7^a, contact-ring 7^c, brush 9, wires 22 and 19. Rack 10 is thus drawn to the 45 right and lamps 13 cut out. The reservoir is again inverted and the mercury fills chamber 1^b ready for action the following night. In the case of a constant-potential circuit the 50 cycle of operations may be continuously repeated, the contacts 6^a 7^a being adjusted, so that switch 15 will be closed at a certain hour and opened at a certain later hour. Obviously this is merely a question of the rate of 55 flow of the mercury and the position of the contacts.

The apparatus has been shown in connection with arc-lamps. It is, however, of gen-

eral applicability wherever a time-operated device is needed to periodically operate or control other apparatus.

Having thus described my invention, what I claim as new, and desire to secure by Letters 55 Patent of the United States, is—

1. A periodic circuit-controller comprising a pivoted reservoir provided with two chambers, a fine duct between them, circuit-terminals sealed into the walls of the chamber, 60 a conducting liquid adapted to be transferred through the duct from one chamber to another, and electromagnetic means for tilting the reservoir when the circuit is closed, whereby continuous operation is effected. 65

2. A periodic circuit-controller comprising a pivoted reservoir provided with two chambers, connecting-channels for permitting a slow transfer of liquid from one chamber to the other, an adjustable contact to close a circuit when a determinate amount of liquid has been transferred to either chamber, and electromagnetic means in the circuit for tilting the reservoir to effect transfer of the liquid to the empty chamber. 70

3. A periodic circuit-controller comprising a rotative reservoir provided with two communicating chambers on opposite sides of the pivot, electromagnets for inverting the reservoir, armatures alternately shifted into operative relation to the magnets, and contacts alternately energizing the electromagnets as the chambers empty. 75

4. A periodic circuit-controller comprising a pivoted reservoir containing two chambers, 80 tubular ducts connecting the bottom of each chamber with the top of the other for permitting a slow transfer from one chamber to the other, contacts actuated by a transfer from either chamber, electromagnetic devices for reversing the reservoir when the contacts are actuated, and connections for operating a controlled apparatus by the periodic changes. 85

In witness whereof I have hereunto set my hand this 8th day of August, 1901.

CARYL D. HASKINS.
